UNITED STATES PATENT OFFICE

2,583,876

HAND TOOL

John E. Penkauskas, Grand Rapids, Mich., assignor to A M I Incorporated, Grand Rapids, Mich., a corporation of Michigan

Application October 10, 1950, Serial No. 189,363

4 Claims. (Cl. 29—268)

1

This invention relates to a tool adapted to apply retaining clips to a panel mounting assembly.

It is the present practice to provide certain types of mechanisms such as cabinets for automatic phonographs, etc., with housings or windows wherein thin panels, particularly transparent panels of glass or plastic, are held in place on extruded metal channels by V-shaped spring clips. Prior to the development of the tool here shown and disclosed, it has been the practice to apply such clips by the use of pliers, screw drivers, or other instruments improvised for the purpose, but it has been found that such practice is slow, laborious, and unnecessarily tiring, and it is consequently the primary object of the present invention to provide a new and improved tool capable of rapid installation of these retaining clips, the tool being so designed as to be capable of easy manipulation, yet quick, smooth, and positive in action.

A further object of the invention is to provide an improved hand tool for the purpose indicated, wherein the tool itself is of relatively simple and inexpensive construction, yet is so designed that it may be easily and quickly loaded with the clip to be applied.

A further object is the provision of a tool of such construction that the clip will not readily be discharged or lost from the tool prior to its application to the work, but will be adequately held in the tool as the tool is manipulated into position, and positively attached to the work upon proper actuation of the tool handles.

These objects are accomplished according to the present teaching by the provision of a small, relatively simple, plier-like hand tool consisting of a pair of levers pivoted together to provide the handles of the tool, with the opposite end portions of the levers so designed and constructed as to act as an operating head. This head portion of the tool includes pilot portions and anchor hooks whereby the tool is operatively secured to the work as the clips are attached. In addition, it includes a shiftable driver for flexing the spring clips and forcing them into their properly assembled position on the work.

A preferred embodiment of the invention is illustrated in the drawings of this application, wherein:

Figure 1 is a perspective view of a hand tool constructed in accordance with these teachings;

Figure 2 is a front elevational view thereof;

Figure 3 is a fragmental sectional view through an edge of a mounting panel, showing the man-

2

ner of application of the tool to the work. In this figure, the tool parts are shown in the position they assume in the first step of the operation;

Figure 4 is a detail sectional view similar to Figure 3, showing an intermediate position through which the tool and clip move during application of the clip to the panel assembly; and

Figure 5 is an enlarged fragmental detail sectional view through a panel supporting member and the edge of a panel carried thereon, with the clip and tool shown in the position which they occupy at the completion of the attaching operation.

The tool disclosed herein is designed for the purpose of applying spring retaining clips to a panel mounting assembly such as illustrated in Figure 5 of the present drawings. In such an assembly a mounting rail 10 having glass supporting flanges 11 and 12 serves to support a panel 13 with the front face 13a on the panel resting against the flange 11 and the edge 13b of the panel bearing against the flange 12. The rail includes an inwardly extending web 14 having a ridge 15 at its inner edge to provide an abutment 16 against which a folded portion 21 of the spring clip 20 may rest. The clip 20 includes a pair of opposite and identical arms 22, each of which has its extreme end 23 bent slightly outwardly so that the lower arm engages the underside of the flange 12, while the upper arm engages the inside surface 13c of the panel 13.

The tool here disclosed is for the purpose of applying the clips 20 to hold the panel 13 in position on the channel 10. The tool is a plier-like assembly as illustrated in Figure 1, and includes levers 25 and 26 pivoted to each other by a cross pin 27. The levers 25 and 26 serve as hand grips, and are normally urged apart by a coil spring 28 slidably mounted on an arcuate spring pilot 29. The lever 25 is slotted at 31 to provide a bifurcated forward end having paired legs 32 spaced apart from each other and offset downwardly at an angle of about 120 degrees with respect to the handle 25. The legs 32 carry a pair of oppositely disposed, spaced apart side plates 33 which are removably attached by dowel pins 34 and machine screws 35. The side plates 33 are preferably of mild steel and include forwardly projecting pilot portions 37 and rearwardly disposed anchor hooks 38 so shaped that as the tool is applied to the work, the pilots 37 are inserted under the flange 12 of the mounting rail 10, while the anchor hooks 38 engage the

abutments 16 on the web 14 to hold the tool in firm engagement with the work as the clips are flexed into position.

As best seen in Figure 1, the legs 32 of the lower handle 25 terminate in shoulders 39 spaced somewhat above the pilot portions 37 of the side plates 33 to provide a pocket 40 in which one of the clips 20 may be manually positioned.

In the preferred form of the invention the handle 25 and its leg portions 32 are formed of hardened tool steel and magnetized so that the legs 32 form the opposite poles of a horseshoe magnet, and the soft iron side plates 33 function as the magnetic pole pieces, whereby a clip of magnetic material will be magnetically held against displacement when once inserted into the pocket 40. By this expedient the clips may be manually placed in the pocket 40 and the tool thereafter applied to the work carrying the clip, in the manner illustrated in Figure 3. The operating end of the lever 26 has a driver portion 41, which extends downwardly from the pivot 27 and has a hardened insert 42 located on its forward surface and positioned to engage the fold portion 21 of a clip carried between the side plates 33. In the commercial embodiment of the invention, the pivot pin 27 is formed of non-magnetic material, so that it will not detract from the efficiency of the magnetic means for securing clips in the socket of the tool. The lever 26 is also non-magnetic.

The sequence of operations involved in applying a clip to the work with the tool here disclosed may be seen from examination of Figures 1, 3, 4 and 5, which show the successive positions of operation. The illustration of Figure 1 shows the tool before the insertion of a clip therein. The first step of the operation is the manual insertion of a clip in the pocket 40, after which the tool is applied to the work by slipping the pilot portions 37 under the flange 12 of the mounting rail and rocking the tool bodily downwardly until the anchor hooks 38 engage behind the abutment surface 16 of the rearwardly extending web 14. The clip is then automatically attached by a quick downward movement of the lever 26 (in the direction of the arrow shown in Figure 3), which forces the hardened facing 42 of the driver 41 inwardly against the fold 21 of the clip, moving it through the position of Figure 4, after which the fold 21 of the clip is snapped downwardly into the final position shown in Figure 5. In this position the opposite arms 22 of the clip are flexed outwardly and the fold 21 is firmly engaged with the abutment 16 of the rail web 14, so that the tool may be removed, leaving the clip locked in position and exerting firm but resilient pressure against the edge of the panel 13.

It has been learned that while the spring clips of a panel mounting assembly such as disclosed in Figure 5 hereof may be applied by various types of improvised tools, yet their application may be rendered easier, faster and more convenient by the use of the tool here disclosed. For one thing, the tool of the present disclosure is so designed as to apply considerable leverage to the clips at the instant of application, so that fairly stiff spring metal may be employed without rendering the installation of the clips unnecessarily difficult.

It is also to be noted that with a tool of the design here illustrated, the tool itself is firmly locked with the mounting rail as the clip is installed, so that the possibility of accidentally dislodging the clip is to a large extent eliminated. The tool is so designed that the clips are self-retaining in the tool socket, so that any likelihood of accidental dislodgement of the clips is overcome, yet the clips may be manually placed in position in the tool without manipulation of any latches, snaps or mechanical retaining devices.

Having thus described my invention, what I claim as new and desire to secure by United States Letters Patent is:

1. A hand tool comprising, in combination, a hand grip comprising a pair of levers pivoted together, with a bifurcated operating end on one of said levers terminating in an open pocket having side plates on each side thereof, with forwardly projecting pilot portions and rearwardly projecting anchor hooks on said side plates, together with a driver carried by the other of said levers and shiftable through said pocket to engage a clip therein and force it therefrom.
2. A hand tool comprising, in combination, a hand grip comprising a pair of levers pivoted together, with an operating end on one of said levers having an open pocket to receive a clip and magnetic means to retain the clip therein, with a forwardly projecting pilot portion and a rearwardly projecting anchor hook on said lever; together with a driver carried by the other of said levers and shiftable through said pocket to engage a clip therein and force it therefrom.
3. A hand tool comprising, in combination, a hand grip with a bifurcated operating end terminating in an open pocket having side plates on each side thereof, with forwardly projecting pilot portions and rearwardly projecting anchor hooks on said side plates, together with a shiftable driver and manually operable means to move said driver through said pocket to engage a clip therein and force it therefrom.
4. A hand tool comprising, in combination, a hand grip with a bifurcated operating end terminating in an open pocket having magnetic means to retain a clip therein, with forwardly projecting pilot portions and rearwardly projecting anchor hooks on said operating end of the tool, together with a shiftable driver and manually operable means to move said driver through said pocket to engage a clip therein and force it therefrom.

JOHN E. PENKAUSKAS.
